FLEXIBLE PULL STRAP FOR AN AERIAL TOY OR THE LIKE

Helmut Karl Bross, Altenberg über Nurnberg, Germany,
assignor of 50 percent to Frank T. Johmann, Berkeley
Heights, N.J.

Filed Apr. 30, 1963, Ser. No. 74,675

Term of patent 14 years

(Cl. D34—15)

FIG. 1

FIG. 2

FIG.3

FIG.4

FIG. 5

FIG. 6

FIG. 7

FIG. 8

FIG. 9

FIG. 10

FIG. 11

FIGURE 1 is a top plan view of the pull strap, showing my new design.

FIGURE 2 is a side view of the pull strap of FIGURE 1.

FIGURE 3 is a cross-sectional view taken along the lines 3—3 of FIGURE 2.

FIGURE 4 is a sectional view taken along the lines 4—4 of FIGURE 1.

FIGURE 5 is a top plan view of the design wherein the teeth of the pull strap have been disposed at an angle.

FIGURE 6 is a side view of the design of FIGURE 5.

FIGURE 7 is a sectional view taken along the lines 7—7 of FIGURE 5.

FIGURE 8 is a top plan view of the design wherein a stop tab has been substituted for a portion of the teeth.

FIGURE 9 is a side view of the design of FIGURE 8.

FIGURE 10 is a sectional view taken along the lines 10—10 of FIGURE 8.

FIGURE 11 is a sectional view taken along the lines 11—11 of FIGURE 9.

I claim:

The ornamental design for a flexible pull strap for an aerial toy or the like, as shown and described.
